PARALLEL TONGUE AND PICKER STICK CHECK FOR LOOMS

John C. Crocker, Ware Shoals, S. C.

Application September 16, 1952, Serial No. 309,879

5 Claims. (Cl. 139—150)

1

This invention relates to an improved parallel tongue adapted to be associated with the usual parallel motions of a loom.

It is an object of this invention to provide an improved parallel tongue adapted to be fixed to the usual picker stick and the parallel shoe with means connecting the parallel tongue to the oscillating stand or foot on which the shoe has rocking movement in unison with the picker stick to maintain the parallel shoe in constant pivotal or rocking relationship with the oscillating parallel.

It is another object of this invention to provide a parallel tongue of the character described having a substantially U-shaped portion on the lower end thereof, the opposite legs of which straddle and slidably engage a transverse shaft carried by the oscillating parallel stand or foot and wherein spring means, in the form of a compression spring disposed in a well or cavity in the lower portion of the substantially U-shaped portion of the parallel tongue engages said transverse shaft or pin and thereby urges the parallel shoe into engagement with the upper surface of the oscillating stand or foot. Since the parallel shoe is curved on the lower surface thereof and the spring means is disposed at approximately the center of the curve, this spring tends to urge the lowest point of the curve into engagement with the oscillating stand or foot and thereby tends to resiliently maintain the picker stick in a substantially vertical optimum position to thereby assist the usual picker stick check, or, as a matter of fact, the spring means may be of such strength as to entirely preclude the necessity of a conventional picker stick check being used at all.

However, in the event that the conventional type of picker stick check is provided, which type of picker stick check is usually carried by the lay of the loom immediately below the shuttle box, it is evident that the improved parallel tongue and the spring means associated therewith will substantially increase the useful life of the picker stick check above that of the picker stick checks heretofore employed.

Some of the objects of the invention having been stated, other objects will appear as the description proceeds when taken in connection with the accompanying drawings, in which—

Figure 1 is a fragmentary elevation of the lower left-hand portion of a loom as though looking from the front of the loom and showing the conventional parallel motion thereon with the improved parallel tongue in association therewith;

Figure 2 is an enlarged end elevation of the

2

parallel motion embodying the improved parallel tongue and looking at the left-hand side of the lower portion of Figure 1;

Figure 3 is an enlarged fragmentary plan view showing the picker stick in cross-section and being taken substantially along the line 3—3 in Figure 1;

Figure 4 is a longitudinal vertical sectional view taken along the line 4—4 in Figure 3, but showing the picker stick, the parallel tongue and the parallel shoe rocked to a different position from that shown in Figures 1, 2 and 3;

Figure 5 is a view similar to Figure 1 but showing a modified form of parallel tongue in association with the parallel motion;

Figure 6 is an enlarged fragmentary end elevation of the parallel motion looking at the left-hand side of the lower portion of Figure 5;

Figure 7 is an enlarged top plan view showing the picker stick in cross-section and being taken substantially along the line 7—7 in Figure 5;

Figure 8 is a longitudinal vertical sectional view through the parallel motion taken substantially along the line 8—8 in Figure 7 and illustrating particularly how the improved parallel tongue can be used without the spring means associated therewith and to still maintain the parallel shoe in proper engagement with the oscillating parallel stand or foot.

Referring more specifically to the drawings, the numeral 10 indicates a loom frame carrying the usual lay rocker shaft 11, to which is secured an oscillating stand or foot 12.

In the form of the invention shown in Figures 1 to 4, inclusive, the usual spring actuated drum 35 having a strap extending therefrom to the picker stick is omitted, since it is not used in this instance. The oscillating parallel stand has a flat-topped outwardly extending plate portion 13 integral therewith which is provided with an opening 14 through which the lower portion of the conventional picker stick 15 loosely extends. The lower portion of the picker stick 15 also loosely extends through an opening 19 in a conventional parallel shoe 16 having a curved lower surface 17

45 which rocks longitudinally upon the oscillating stand 12, and also oscillates therewith, as is customary. The picker stick 15 is fixed to the parallel shoe 16 by a bolt 20 which penetrates an upwardly projecting portion 21 integral with the shoe 16 and said bolt 20 also penetrates a conventional washer 22 which serves to clamp the picker stick 15 against the upwardly extending portion 21 of the parallel shoe 16. Of course, 50 the improved tongue, to be presently described,

is interposed between the projection 21 of the parallel shoe 16 and the picker stick 15.

The picker stick 15 is actuated by any suitable means, such as a lug strap indicated at 24. The foregoing description is that of the conventional elements of a loom with which the present invention is adapted to be associated.

The improved parallel tongue is broadly designated at 30 and comprises a substantially U-shaped yoke portion 31 having spaced parallel 10 upwardly extending arms or legs 32 and 33, the leg 33 being substantially longer than the leg 32 and extending upwardly through the opening 19 and the parallel shoe 16 and being suitably secured to the inner surface of the picker stick 15 by a bolt 20. The leg 33 of the parallel tongue 30 really forms a J-shaped member and is preferably provided with flanges 34 on opposed sides thereof between which the lower portion of the picker stick 15 fits. The upper end of the inner 20 arm 32 of the U-shaped or yoke portion 31 of the parallel tongue 30 preferably terminates against or in closely spaced relation to the lower curved surface 17 of the parallel shoe 16. The yoke portion 31 and the lower surface of the 25 shoe define a transversely extending opening.

In the form of the invention shown in Figures 1 to 4, inclusive, the yoke 31 is provided with a downwardly extending well portion 35 having a cavity 36 therein which is open at the juncture of the legs or arms 32 and 33 of the yoke 31. The cavity 36 has a compression spring 37 loosely mounted therein, the lower end of which engages a disk 38 and the upper end of which engages the lower end of a spring guide 40 having a curved upper surface which is urged into engagement with the peripheral surface of a bushing 41 slidably and oscillatably mounted on a transverse shaft 42 fixed on opposite walls of the opening 14 in the oscillating stand 12.

The spring guide 40 preferably has a reduced portion 43 integral therewith about which several turns of the upper portion of the compression spring 37 are disposed to maintain the spring 37 in proper relation to the spring 37. The lower surface of the disk 38 is engaged by an adjustment screw 44 which threadably penetrates the closed lower end of the well portion 35 and has a lock nut 45 thereon for adjusting the force exerted by the compression spring 37 against the shaft 42 or the bushing 41. Thus, the compression spring urges the central portion of the lower surface 17 of the parallel shoe 16 toward the upper flat surface of the oscillating parallel stand or foot 12 and thereby tends to maintain the picker stick 15 in an optimum vertical position. It is evident that when the picker stick is moved outwardly in the usual manner by the impact of the usual shuttle, not shown, the compression spring 37 will tend to return the picker stick 15 to substantially vertical position. On the other hand, upon the picker stick being actuated by the means 24 to throw the shuttle across the usual lay, the inner end of the parallel shoe 16 will then engage the upper surface of the oscillating parallel stand or foot 12 with the result that the compression spring 37 will again tend to return the picker stick 15 to the substantially vertical position as shown in Figure 1.

Of extreme importance is the fact that, heretofore, upon oscillation of the shoe 16 relative to the parallel stand or foot 12, the parallel shoe 16 has had a tendency to slide along the upper surface of the oscillating parallel stand 12 with the result that the picker stick may not be in proper

position to be engaged by the shuttle when boxed or when discharged from the shuttle box and, of course, this has caused undue wear of the curved surface 17 of the parallel shoe 16. Also, the spring 37 associated with the parallel tongue 30 obviates the necessity of providing the usual heel strap, spring, spring shell and stud of the parallel motion thus providing a parallel motion which may be much more economically produced than the usual types of parallel motions and obviating the necessity of replacing the usual heel strap periodically.

It is evident that the position of the picker stick 15 and the parallel tongue 30 may be adjusted relative to the shoe 16 by means of a set screw 46 which threadably penetrates the upper portion of the upwardly extending projection or portion 21 of the parallel shoe 16 and bears against the corresponding surface of the leg or arm 33 of the parallel tongue 30, the adjustment screw 46 being maintained in the proper position by a lock nut 47. Of course, the use of an adjustment screw 46 is well known and it is described to illustrate that the instant parallel tongue 30 may readily replace the conventional type parallel tongue with equal facility.

Modified or second form of the invention

In Figures 5 to 8, inclusive, there is shown a modified form of parallel tongue 30' in association with the conventional parallel motion and those parts of the parallel motion which have been described heretofore with respect to the original form of the invention shown in Figures 1 through 4, inclusive, will bear the same reference characters in the form of the invention shown in Figures 5 to 8, inclusive, with the prime notation added. Also, the form of parallel tongue shown in Figures 5 to 8, inclusive, is substantially similar to the parallel tongue shown in Figures 1 through 4, inclusive, with the exception that the compression spring 37, and the well portion 35 are omitted in the form of the invention shown in Figures 5 to 8, inclusive, and, therefore, the modified form of parallel tongue 30' also bear the same reference characters as the form of parallel form shown in Figures 1 to 4, inclusive, with the prime notation added.

The modified form of parallel tongue 30' is particularly provided to facilitate the use of the conventional heel strap and the usual spring means associated therewith for normally urging the lower end of the picker stick 15' inwardly toward the loom frame 10' and for, conversely, normally urging the upper end of the picker stick 15' adjacent the usual end plate of the shuttle box.

The conventional heel strap 50 is fixed on the bolt 20' between the picker stick washer 22' and the outer surface of the picker stick 15' and is thus clamped to the outer surface of the picker stick 15' in the usual manner. The heel strap 50 extends inwardly and approximately surrounds a conventional spring shell 51 to which the heel strap is suitably secured and which shell 51 is oscillatably mounted on a stud 52 carried by the oscillating parallel stand or foot 12'. A conventional torsion spring 53 is also mounted on said stud 52 and normally urges the spring shell 51 in a counter-clockwise direction in Figure 8 to thereby maintain proper tension in the heel strap 50.

As heretofore stated, the modified form of parallel tongue 30' is substantially similar to the original form of parallel tongue 30 and includes the yoke portion 31' having the arms 32' and

33' integral therewith. However, the yoke portion 31' of the parallel tongue 30' is devoid of the well portion and a spring and associated parts such as that shown in Figure 4 and indicated by the reference character 35, 38, 44 and 45, inclusive. Thus, the modified form of parallel tongue 30' does not function to maintain the picker stick 15' in a substantially vertical position as does the form of parallel tongue 30, however, the legs or arms 32 and 33 thereof engage opposite surfaces or substantially diametric opposed surfaces of the bushing 41' to thereby maintain the parallel shoe in proper relation to the upper surface of the oscillating stand or foot 12' during operation thereof. This insures that the portion of the heel strap 50 which is disposed against the outer surface of the picker stick 15' cannot swing outwardly relative to the oscillating parallel stand 12' as heretofore has been the case, and thus prevents the outer portion or wall of the opening 14' in the oscillating parallel stand 12' from cutting or damaging the heel strap 50.

Of course, this also insures that the curved lower surface 17' of the parallel shoe 16' will merely rock against the upper surface of the oscillating parallel stand 12', rather than sliding thereagainst, with a resultant smoother operation and thereby lengthening the useful life of the parallel shoe 16'.

Although other stabilizing devices have heretofore been provided in association with the parallel motions, they have been relatively complicated and cumbersome and thus costly in manufacture as compared to the embodiment of the parallel tongue of the instant invention.

In the drawings and specification there has been set forth a preferred embodiment of the invention, and although specific terms are employed, they are used in a generic and descriptive sense only and not for purposes of limitation, the scope of the invention being defined in the claims.

I claim:

1. An improvement in a parallel motion for picker sticks in a loom having a oscillatable parallel provided with an elongated longitudinally extending slot through which the picker stick extends and having an oscillatable shoe mounted on the parallel and having an elongated slot through which the picker stick passes and means for securing the picker stick to the shoe, the improvement comprising a bolt spanning the slot in the parallel, a J-shaped member disposed in said slots and having its longer leg secured to the picker stick and shoe and having the lower portion of the longer leg and the shorter leg disposed on opposed sides of said bolt in the parallel.

2. An improvement in a parallel motion for picker sticks in a loom having an oscillatable parallel provided with an elongated longitudinally extending slot through which the picker stick extends and having an oscillatable shoe mounted on the parallel and having an elongated slot through which the picker stick passes and means for securing the picker stick to the

shoe, the improvement comprising a bolt spanning the slot in the parallel, a J-shaped member disposed in said slots and having its longer leg secured to the picker stick and shoe and having the lower portion of the longer leg and the shorter leg disposed on opposed sides of said bolt in the parallel, and spring pressed means in the lower portion of the J-shaped member engaging the lower surface of said bolt for urging the shoe against the parallel.

3. An improvement in a parallel motion for picker sticks in a loom having an oscillatable parallel provided with an elongated longitudinally extending slot through which the picker stick extends and having an oscillatable shoe mounted on the parallel and having an elongated slot through which the picker stick passes and means for securing the picker stick to the shoe, the improvement comprising a bolt spanning the slot in the parallel, a J-shaped member disposed in said slots and having its longer leg secured to the picker stick and shoe and having the lower portion of the longer leg and the shorter leg disposed on opposed sides of said bolt in the parallel, the lower end of the J-shaped member having a well therein and resilient means mounted in the well and urged upwardly against the lower side of said bolt.

4. An improvement in a parallel motion for picker sticks in a loom having an oscillatable parallel provided with an elongated longitudinally extending slot through which the picker stick extends and having an oscillatable shoe mounted on the parallel and having an elongated slot through which the picker stick passes and means for securing the picker stick to the shoe, the improvement comprising a bolt spanning the slot in the parallel, a member secured to the front edge of the picker stick and extending through the slots in the shoe and parallel and having a transverse opening in its lower end penetrated by said bolt.

5. An improvement in a parallel motion for picker sticks in a loom having an oscillatable parallel provided with an elongated longitudinally extending slot through which the picker stick extends and having an oscillatable shoe mounted on the parallel and having an elongated slot through which the picker stick passes and means for securing the picker stick to the shoe, the improvement comprising a bolt spanning the slot in the parallel, a member secured to the front edge of the picker stick and extending through the slots in the shoe and parallel and having a transverse opening in its lower end penetrated by said bolt and resilient means in said member secured to the front side of the picker stick engaging the lower side of said bolt for urging the shoe against the parallel.

JOHN C. CROCKER.
